UNITED STATES PATENT OFFICE.

GEORGE HENRY WHEARY, OF RACINE, WISCONSIN.

AUTOMATIC TRUNK-LOCK.

1,172,231.

Specification of Letters Patent. Patented Feb. 15, 1916.

Application filed February 24, 1914. Serial No. 820,390.

To all whom it may concern:

Be it known that I, GEORGE H. WHEARY, a citizen of the United States, and resident of Racine, in the county of Racine and State of Wisconsin, have invented new and useful Improvements in Automatic Trunk-Locks, of which the following is a description, reference being had to the accompanying drawings, which are a part of this specification.

This invention relates to improvements in automatic trunk locks more particularly adapted for trunks which are locked or bolted at a plurality of points.

In trunks of the ordinary type, the covers or sections are provided with one lock and a plurality of bolts or other locking devices to securely fasten the parts together, and in wardrobe and other trunks of the better type a plurality of keyed locks are used for each cover or section. In the trunks of the type last mentioned, the locks are independently unlocked and the bolts or other locking means are independently actuated to release the cover or section. The operation of the different devices requires time and in some cases the bolts or other locking means are difficult to unlock.

It is one of the objects of the present invention to eliminate the before mentioned objectionable features and provide a trunk with a plurality of locks which may be unlocked by the use of a key engaging one of the locks.

A further object of the invention is to provide an automatic trunk lock adapted to lock a trunk cover or section at a plurality of points, the lock being so constructed as to be actuated to simultaneously unlock the securing means at the different points.

A further object of the invention is to provide an automatic trunk lock which is of simple construction, is strong and durable and which is well adapted for the purpose described.

With the above and other objects in view, the invention consists of the improved automatic trunk lock and its parts and combinations as set forth in the claims and all equivalents thereof.

In the accompanying drawing in which the same reference characters indicate the same parts in all of the views, Figure 1 is a front view of a trunk provided with the improved automatic lock; Fig. 2 is a vertical longitudinal sectional view of the trunk showing the portions of the locking means

within the trunk; Fig. 3 is a horizontal sectional view thereof on a larger scale, taken on line 3-3 of Fig. 2; and Fig. 4 is an inner face view of the main lock and a portion of the locking bar, portions of the locking bar being broken away to show interior construction.

Referring to the drawing the numeral 8 indicates a trunk body and 9 the hinged cover thereof which is locked to the body portion when in closed position by hasp locks 10 and 10' mounted on the respective front portions of the trunk near the opposite ends thereof. The trunk is also provided with fixtures 11 which serve to hold the adjacent edges of the cover and body portion in alinement.

The hasp lock 10' comprises the hinged hasp member 12 fastened to the cover and the hasp plate 13 fastened to and set into the body portion of the trunk. The hasp plate is provided with a spring actuated latch member 14 which lockingly engages the eye portion 15 of the hinged hasp member 12 when sprung to closed position. The shank of the bolt 16 of the latch member 14 is connected by a chain 17, or other flexible connection which will yield in one direction, to a slidably bar 18 mounted on the inner face of the front wall of the trunk body. The bar is slidably held by straps 19 and the portion of the bar which engages one of these straps is formed of less width to provide shoulders 20. These shoulders serve as stops which engage the strap to limit the longitudinal play of the bar. The opposite free end of the bar terminates at a point in the rear of the hasp lock 10 and is provided with a bolt opening 21 the purpose of which will be described later.

The hinged hasp member 22 carries a Yale or other suitable lock 23 which is provided with transversely movable bolts 24. These bolts have inclined or beveled ends 100 25 so they will snap into locking position with the inner edge of the hasp plate 26 which is mounted on and set into the body portion of the trunk. A key 27 controls the movement of lock bolts 24 toward each other to disengage the hasp plate and thereby unlock the trunk in the ordinary manner. Each hinged hasp member is provided with a flat spring 28, which automatically swings the hinged portion of said member 105 outwardly when released by the bolts or latch in the ordinary manner.

One of the bolts is provided with an inwardly extending pin or projection 29 which is adapted to enter the opening 21 of the bar 18 when the hasp member 22 is moved to closed position. In order to insure the entrance of the pin 29 in the opening 21, the pin is made sufficiently long to enter the said opening before the bolts are moved by engaging the hasp plate.

10 While the automatic lock is shown in connection with a trunk, it is to be understood that it may also be used for locking other containers and doors without departing from the spirit and scope of the invention.

15 It is also to be understood that the other lock bolt may also be provided with a pin adapted to engage a locking bar in the same manner before described with relation to the first mentioned bolt.

20 It is to be further understood that while the specification and the drawing disclose but one form of the invention that the construction may be modified in many ways without departing from the spirit and scope 25 of the invention as defined in the claims.

What I claim as my invention is:

1. An automatic lock, comprising a hasp latch member, a hasp lock member spaced therefrom, and a means connecting the two members together when the lock member is in locked position, said connecting means unlocking the latch member when the lock member is unlocked.

30 2. An automatic lock, comprising a latch member, a hinged hasp member lockingly engaged thereby, a hasp plate, a hinged hasp member provided with a bolt having a locking engagement with the plate, and a means connected to the latch member and extending to a position adjacent to the hasp plate and engaged by the bolt for unlocking the latch member when the last mentioned hasp member is unlocked from the plate.

35 3. An automatic lock, comprising a spring actuated latch member, a hinged hasp member lockingly engaged thereby, a hasp plate spaced therefrom, a hinged hasp member

having a lock which lockingly engages the plate and also having a projecting portion extending from one of its movable parts, 50 and a bar connected to the latch member and extending to a position adjacent to the projection of the lock and engaged and moved thereby to unlock the latch member when the lock is unlocked from the plate. 55

4. An automatic lock, comprising a spring actuated latch member, a spring actuated hinged hasp member lockingly engaged thereby, a hasp plate spaced from the latch member, a hinged hasp member having a 60 slideable bolt which lockingly engages the plate and also having pin-like portion projecting from the slideable bolt, and a bar having a connection with the latch and provided with an opening into which the pin 65 portion extends when the lock engages the plate to unlock the latch member when the lock is unlocked from the plate, the connection between the bar and the latch permitting the latch to freely move in one 70 direction.

5. An automatic lock, comprising a spring actuated latch member, a spring actuated hinged hasp member, lockingly engaged thereby, a hasp plate spaced from 75 the latch member, a hinged hasp member having a lock which lockingly engages the plate and also having pin-like portion projecting from a movable portion of the lock, a bar having a connection with the latch 80 and provided with an opening into which the pin portion extends when the lock engages the plate to unlock the latch member when the lock is unlocked from the plate, the connection between the bar and the 85 latch permitting the latch to freely move in one direction, and means for limiting the movement of the bar.

In testimony whereof, I affix my signature, in presence of two witnesses.

GEORGE HENRY WHEARY.
